NEWTON C. KEELING, OF DANBURY, CONNECTICUT.

AUTOMATIC TRAIN-STOPPING MECHANISM.

1,391,255.

Specification of Letters Patent. Patented Sept. 20, 1921.

Application filed March 3, 1920. Serial No. 362,946.

To all whom it may concern:

Be it known that I, NEWTON C. KEELING, a citizen of the United States, residing at 53 West St., Danbury, county of Fairfield, State of Connecticut, have invented an Improvement in Automatic Train-Stopping Mechanism, of which the following is a specification.

This invention has for its object to provide automatic train stopping mechanism which will be simple in its construction and efficient and reliable in its action. The stopping mechanism of the present invention is located on the locomotive and co-operates with an electrically operated system which sets a danger signal against a following train while a leading train remains in a block, and causes the stopping mechanism to act to throw on the brakes of the following train as it approaches an occupied block.

The construction and operation of the novel automatic train stopping mechanism, as well as its connection with the system, will now be fully described.

25 In the accompanying drawing forming a part of this specification,

Figure 1 is a view of the novel train stopping mechanism, partly in section and partly in elevation, disclosing the parts in the positions which they normally occupy when the brakes are unapplied, and showing a locomotive in dotted lines;

Fig. 2 a similar view showing the parts in the positions which they assume as the locomotive approaches an occupied block and the brakes are applied, and also showing a portion of the electrically operated system; and

Fig. 3 is a diagrammatic view illustrating the electrically operated system with which the automatic train stopping mechanism has connection.

Referring to Figs. 1 and 2, 10 denotes a battery, 11 a solenoid, 12 a compressed air cylinder, and 13 a stopping cylinder having therein a loose piston 14. 15 denotes a rod having enlarged ends 16 and 17 and a handle 18. Enlarged end 16 is arranged for upward and downward sliding in the solenoid, and enlarged end 17 is slidably fitted in a guide 19 on the locomotive. The stopping cylinder has connection at one of its ends with brake pipe 20, that is, the pipe leading to the brakes (not shown), and at its other end it is connected by means of a short pipe 21 with a pipe 22 leading from the com-

pressed air cylinder, the connection between pipes 21 and 22 being denoted by 23. At 24 and 25 are represented quick acting valves in pipe 22, one above and the other below connection 23, which are operated by parallel levers 26 and 27, respectively, the latter being pivotally attached to the rod in any approved manner, as indicated at 28 and 29. It may here be remarked that when rod 15 is in its extreme upward position, enlarged portion 16 is in engagement with the solenoid and valve 24 is open. When the rod is in its extreme downward position, valve 24 is closed. When valve 24 is open, valve 25 is closed, and vice versa. End 30 of pipe 22 leads to the atmosphere, as do also ports 31 in the stopping cylinder.

The brake pipe shown is normally filled with air under pressure from any source, the action of the air in this pipe retaining the brakes released. In other words, the train brake used in connection with the present invention operates on the balanced system, the brakes being set by pressure in another pipe (not shown) when the pressure in pipe 20 is relieved. Brake mechanism is not illustrated as it forms no part of the present invention. A slightly higher pressure is maintained in the compressed air cylinder than is maintained in the brake pipe, so that when valve 24 is open the excess pressure holds the loose piston against the end of the stopping cylinder which connects with the brake pipe, as it is shown in Fig. 1. The ports leading to the atmosphere are thus covered and no air can escape from the brake pipe. In this position of the loose piston the brakes remain unapplied. However, when valve 24 is closed, the pressure to the left of the loose piston, as shown in Fig. 1, is removed, and the pressure in the brake pipe forces the loose piston to the opposite end of the stopping cylinder, as it is shown in Fig. 2. The ports are thus successively uncovered so that air from the brake pipe passes to the atmosphere and the pressure in said pipe is gradually relieved and the brakes are gradually applied, as will be readily understood. The trapped air to the left of the loose piston, as shown in Fig. 1, escapes through valve 25 and outlet end 30 of pipe 21. 32 denotes insulated electric connections and 33 is an insulated case. Embedded in opposite sides of the case are contacts 34 which are in circuit with connections 32. Brackets 35 slidably support shanks 36

carrying springs 37, contact shoes 38 and shoulders 39, the springs being arranged between the lower ends of the brackets and the contact shoes to normally hold the shoes in their extreme downward position, and the shoulders being arranged to rest against the upper ends of the brackets to limit the downward movement of the shanks, as will be readily understood. One of the shanks is 10 extended beyond its shoulder to provide a plunger 40 which is adapted to slide in the insulated case. When the contact shoes are in their normal position, the plunger is in engagement with the contacts in the insulated case and completes a circuit which passes from the battery, and through the solenoid and connections, and the solenoid is thus energized. It will be apparent that when rod 15 is raised to its extreme upward 15 position, enlarged portion 16 thereof will be held to the solenoid so long as it is energized, and as has been stated, valve 24 will be open and valve 25 closed. It will also be apparent that the solenoid will be energized so long as the plunger remains in engagement 20 with contacts 34. 41 denotes independent connections between connections 32 and the contact shoes.

Referring now to Fig. 3, 42, 43 and 44 30 denote the track rails in separate blocks. Ramp rails 45 are placed in position to be engaged by the contact shoes at a safe braking distance before a locomotive passes from one block into another, and each block is 35 provided with a complete and separate electrically operated system. Character A denotes an ordinary signaling relay, and B denotes a second relay controlled by the circuit which operates the ordinary relay. As 40 shown, there are arranged in this circuit electromagnets 46 and 47, the former provided with an armature 48 and the latter having an armature 49. Controlled by the ordinary relay is a signal 50, in the present 45 instance an ordinary semaphore which is adapted to be held in the raised or danger position by a counterweight 51 and to be drawn to its lowered or clear track position by an electric motor 52, and a battery 53 in circuit with the motor and armature 48. 54 Denotes a battery in circuit with the rails of a block and with electromagnets 46 and 47.

The circuit which operates the ordinary 55 and the second relay is normally closed. This circuit, denoted by 55, extends from battery 54 to one of the rails, thence through electromagnets 46, thence through electromagnets 47, thence to the other rail, and thence back to the battery. Consequently, 60 electromagnets 46 and 47 are normally energized and armatures 48 and 49, respectively, are in contact therewith, so that battery 53 in the ordinary relay causes a current 65 to flow through connections 56, contact

57, armature 48 and motor 52, the motor being thus operated to retain the signal in the clear track position, as will be readily understood, and connections 58 which extend from the ramp rails, are in contact with each other by reason of the engagement of armature 49 with contact 59. However, when a locomotive is in a block, as denoted at 60 in block 44, circuit 55 of that block will be short circuited, the current then passing 70 from battery 54 along connection 61 to one of the rails, thence along the rail to the axle of locomotive 60, thence across the axle to the other rail, thence on the rail as indicated by 62, and thence back to the battery along 75 connection 63. Armatures 48 and 49 will then be released from their respective electromagnets, the signal will be in its danger position, and there will be no contact between connections 58 leading from the ramp 80 rails.

As has been stated hereinbefore, the contact shoes are normally in their extreme downward position, and in this position of said shoes the circuit in the locomotive is 90 continuous, the solenoid is energized, and rod 15 holds the levers so that valve 24 is open and valve 25 is closed. As the locomotive traveling in the direction indicated by the arrow in Fig. 3, approaches a block, 95 the contact shoes ride up on the ramp rails, as indicated in Fig. 2. If the block ahead is clear, the signal will be set at clear and armature 49 will be held by electromagnet 47 and in engagement with contact 59. When 100 now the contact shoes ride up on the ramp rails, the plunger will be slid up in the insulated case so that it disengages the contacts therein, but a complete circuit will be had through connections 41, connections 58, 105 armature 49 and contact 59, so that the solenoid will remain energized and the rod will remain in its extreme upward position. As the contact shoes run off of the ramp rails, the plunger will be again in engagement 110 with the contacts. Suppose now that the block ahead is occupied. The axle of the train in said occupied block will short circuit the operating circuit for the relays, armatures 48 and 49 will be removed from their 115 electromagnets, the signal will be in its danger position, and there will be no connection between the ramp rails, as will be readily understood. Accordingly, as soon as the contact shoes ride up on the ramp 120 rails, the circuit in the locomotive will be broken, thus deenergizing the solenoid so that rod 15 will immediately drop by gravity. Valve 24 will now be in its closed position and valve 25 will be open. Consequently, the brakes will be applied as hereinbefore fully described. The arrangement is such that when the enlarged portion of the rod leaves the solenoid, it will not again engage it until the handle of the rod is 125 130

grasped and the rod manually lifted. It will be apparent that when the leading train passes out of the block and the signal is automatically set to clear, the rod may be 5 conveniently lifted to remove the pressure from the brakes.

What I claim is:—

1. Automatic train stopping mechanism comprising a compressed air cylinder having extending therefrom a pipe provided with two valves and an outlet end, a stopping cylinder provided with ports and carrying a loose piston, a pipe connecting the stopping cylinder with the compressed air cylinder pipe at a point between its valves, means consisting of a solenoid in circuit for holding one of the valves open and the other closed, automatic means for breaking the circuit to change the position of each valve, 10 a brake pipe having connection with the stopping cylinder, and subsequently operable automatic means associated with said circuit breaking means for closing the circuit.
2. Automatic train stopping mechanism comprising a pressure reservoir, a pipe extending therefrom and having an outlet end communicating with the atmosphere, a pair of spaced, oppositely arranged valves in said 15 pipe, a stopping cylinder provided with outlet ports, a loose piston therein, connection between one end of said cylinder and a train pipe, connection between the opposite end of said cylinder and the pressure reservoir pipe at a point intermediate the valves 35 therein, lever mechanism on said valves for simultaneous operation thereof, and electrically actuated means for operating the said lever mechanism.
3. Automatic train stopping mechanism 20 comprising a pressure reservoir, a pipe extending therefrom and in communication with the atmosphere at its end, a pair of oppositely arranged, spaced valves in said pipe, a stopping cylinder provided with outlet ports and a loose piston therein, connection between one end of said cylinder and said pipe intermediate the valves, connection between the opposite end of said cylinder and a train pipe, operating levers 45 on said valves, a rod connecting said levers for simultaneous operation thereof, electrically actuated means for automatically moving said rod to open one of said valves and close another, and automatic mechanism 50 for control of said electrically actuated means.

In testimony whereof I affix my signature.

NEWTON C. KEELING.
